BAG

Howard A. Wolf, Philadelphia, Pa., assignor to
Wolf Brothers, a partnership composed of Louis
Wolf, Elias Wolf, Howard Wolf, and Walter
Wolf, Philadelphia, Pa.

Application November 11, 1935, Serial No. 49,178

1 Claim. (Cl. 229—68)

The present invention relates to an improvement in bags for receiving articles of merchandise, and it relates more particularly to an improvement in bags of the locking and carrying type wherein an aperture is centrally provided near the open end of the bag for receiving a locking tab carried on a foldable flap extending beyond said open end, and for simultaneously providing a convenient handle whereby said bag may be carried by hand.

An object of the present invention is to provide means for securely closing those portions of the open bag end which are spaced a substantial distance from the central aperture, and thus prevent gaping of the bag end at these points.

Another object of the present invention is to provide improved means for effecting such closure.

With the above and other objects in view, which may appear more fully from the following detailed description and the accompanying drawing, the present invention consists of a bag generally open at one end and having a foldable flap extending beyond said open end, a centrally located transverse aperture extending through the bag near the open end thereof, means for centrally securing said foldable flap in its folded or bag closing position comprising a tab carried by said foldable flap and adapted to be folded through said aperture, and means for securing said foldable flap in a folded or bag-closing position at points along the open bag end removed from said central locking means and comprising a plurality of gummed areas on the face of said bag on either side of said transverse aperture and spaced therefrom, and a plurality of correspondingly spaced gummed areas on the juxtaposed face of said foldable flap and spaced from the edges thereof.

For the purpose of illustrating the present invention, there is shown in the accompanying drawing one form thereof which has been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the drawing in which like reference characters indicate like parts:

Figure 1 is an elevation of a bag exemplifying one form of the invention, the bag being in open condition.

Figure 2 is a section on the line 2—2 of Figure 1, looking in the direction of the arrows.

Figure 3 is a fragmentary elevation of the bag shown in Figure 1 as it appears when closed.

Figure 4 is a section of the bag shown in Figures 1, 2 and 3, as it appears when closed, taken on the same plane as Figure 2.

The embodiment of the invention illustrated in Figures 1, 2, 3 and 4 is a bag or container 14, generally of known form, having a body portion 10 composed of a blank folded at 14' to form two plies 15 and 16 integral along one end of the bag and suitably connected along the edges as indicated at 17, 17. Ply 16 has a flap 18 united therewith along a fold line 19 and which normally lies in the plane of the ply 16 when the bag is open, but which may be folded down along line 19 to close the mouth 14a of the bag when desired and as is usually done when an article has been placed in the bag.

In order to seal the bag 14, flap 18 and ply 15 have thereon gummed areas 20, 20 and 21, 21, respectively, so disposed that each area 20 registers with an area 21 when flap 18 is folded down along line 19. The adhesive material on areas 20 and 21 is of a character which does not adhere to paper in contact therewith, so that bags such as 14 can be stacked in a pile without causing trouble from their sticking together. When, however, a gummed area 20 is pressed against a gummed area 21, the adhesive layers coalesce and fasten the flap 18 down to close the mouth 14a of the bag. Suitable adhesive for use on the gummed areas 20 and 21 may be made by dissolving para rubber in organic (benzol, etc.) or other volatile rubber solvent. A natural or artificial aqueous dispersion of raw rubber may also be used (such as latex). When such a solution or dispersion is applied to the surface of the bag, the liquid in the composition carries some of the rubber into the pores or fibres of the bag so that when the liquid evaporates a layer of gum or adhesive of the desired character is fixed on the treated areas of the bag.

It will be observed that the gummed areas 21 on ply 15 are not only spaced from each other as indicated at 15', but are spaced from the edge of ply 15 at the mouth 14a of the bag by an ungummed strip 15a of ply 15, as well as from the side edges of ply 15 by ungummed areas 15b, 50 15b, so that there is no chance of the gum, when in solution, spreading to the mouth of the bag or to the outside of ply 16. Also flap 18 has an ungummed area 18' which separates the gummed areas 20, and the areas 20 further are spaced 55

from the free edge at the end of the flap 18 by an ungummed strip 18a, as well as from the side edges of the flap 18 by ungummed areas 18b, 18b.

5 The bag or container 14 is illustrated as having also other means for connecting flap 18 to ply 15 in addition to the gummed areas. Such additional means is of known character and comprises an aperture 22 in ply 15 and a pair of 10 wings 23, 23 on flap 18 formed by cuts 24, 24 which extend from the free edge of such flap inwardly and then toward each other. By bending the wings 23 they may be passed through aperture 22 so as to contact with the inner face 15 of ply 15 when the flap 18 is folded down as shown in Figures 3 and 4.

While I have illustrated one embodiment of the present invention, it will be understood that the scope of the invention is to be derived from 20 the appended claim rather than from the description and drawing.

Having thus described the invention, what is hereby claimed as new and desired to be secured by Letters Patent is:

25 A bag for receiving articles of merchandise for carrying, being generally open at one end and

having a flap extending beyond said open end, a centrally located aperture extending transversely through the bag near the open end thereof, through which the hand may be extended for holding the bag pendently; said flap being adapted to be folded over the open end of the bag and having a tab formed therein adapted to be folded into said transverse aperture in the body of the bag thereby forming central locking means, a similar gummed area on the face of said bag on 10 either side of said transverse aperture and spaced therefrom, said areas extending near to but not quite up to the edges of the bag and of said aperture and being also spaced from the open end thereof, and a corresponding pair of 15 similarly spaced gummed areas on the juxtaposed face of said flap and spaced from the edges thereof, whereby, by folding over the flap and pressing together the corresponding gummed areas, those portions of the bag opening which do not 20 adjoin the transverse aperture but are spaced a substantial distance therefrom may be securely closed, and whereby the central portion of the bag opening may be closed by means of the coacting flap tab and the central transverse aperture. 2

HOWARD A. WOLF.
